OXYGEN DEMAND REGULATOR

Leonard A. Wiggins, Akron, Ohio

Application January 25, 1946, Serial No. 643,452

20 Claims. (Cl. 128—140.1)

1
This invention relates to improvements in oxygen regulators of the demand type wherein oxygen is passed through a mask into the mouth or nose of a person using the regulator as such person inhales.

An object of the invention is to provide an oxygen regulator of the demand type which is absolutely reliable under all conditions of service, the oxygen flow being under control so as to furnish the proper amount of oxygen at all times.

Another object is to provide an oxygen regulator of the type referred to wherein the oxygen, or other gas, is made available to the user with the least possible exertion on his part, it being only necessary to inhale normally to insure receiving an adequate supply. Thus the regulator is suitable for use at high altitudes, for supplying oxygen to patients in hospitals and for administering certain types of anaesthetics.

A further object is to provide a regulator of the type referred to having a chamber in which a diaphragm is mounted for movement by inhalation of the user, against the action of a spring which tends to return the diaphragm to its initial position, said diaphragm being connected to a small shaft which operates a bell crank arrangement that moves a pilot or primary slidable valve to admit oxygen under pressure from a passageway leading from a source of supply into a pilot chamber.

A further object is to provide a secondary valve operated by the pressure of the oxygen in the pilot chamber, to admit oxygen from a high pressure chamber into a passageway from which it may be inhaled by the user of the device.

A further object is to provide an arrangement whereby if the pressure of the oxygen in the pilot chamber is not sufficient to operate the secondary valve or to open the latter enough to let the desired amount of oxygen through the secondary valve, the latter may be operated mechanically by movement of the primary valve in engagement with the secondary valve, which movement may be accomplished by an increase in the inhalation of the user through movement of the diaphragm.

A further object is to provide a separate passage from the pilot chamber into the passageway leading to the breather, which passage is closed by a pressure valve which will be unseated when the pressure in the pilot chamber builds up to a desired maximum, so as to avoid locking the secondary valve open unduly long at the end of the inhalation.

Other objects and advantages will become apparent from the following description taken in conjunction with the accompanying drawings.

In the drawings:

Fig. 1 is a perspective view of the regulator;

Fig. 2 is a longitudinal sectional view through

2
the regulator with the parts in their initial position;

Fig. 3 is an enlarged fragmentary view of the passage leading into the pilot chamber and the primary valve closing the passage;

Fig. 4 is a view similar to Fig. 2 with the primary valve moved by the diaphragm and bell crank arrangement, and with the secondary valve opened by pressure in the pilot chamber;

Fig. 5 is a fragmentary view somewhat similar to Fig. 4, except that the secondary valve is shown opened by the mechanical action of the primary valve;

Fig. 6 is a transverse section taken substantially on line 6—6 of Fig. 2; and

Fig. 7 is a similar fragmentary section taken substantially on line 7—7 of Fig. 2.

Referring to the drawings the numeral 10 designates a housing as a whole, preferably formed of aluminum or other suitable material, having a rectangular body portion 11 and an annular upper portion 12, as viewed in the drawings. A cover plate 13, preferably formed of the same material as the housing, cooperates with the portion 12 to form a diaphragm chamber that receives a rubber or rubberized fabric diaphragm 14, which divides the chamber into an outer chamber 15 and an inner chamber 15'. The cover plate is secured to portion 12 by screws 16, or the like, and is 25 perforated as at 17 so that the outer diaphragm chamber 15 will be in communication with the atmosphere. As clearly shown in Figs. 2, 4 and 6, the outer edge of the diaphragm is provided with a bead 18 of conventional material that is 30 suitably clamped between cover plate 13 and portion 12 of the housing so as to have ample room for movement of the diaphragm as hereinafter described.

The rectangular portion 11 of the housing is 35 provided with a longitudinal bore 19 that extends from the rear end of the housing to the surface 20, after which the bore is reduced in size at 21. Portion 11 is also provided near its front end with a diagonal passageway 22 that leads from the inner diaphragm chamber 15' into a transverse passageway 23 that extends partially across the front of the housing and joins a longitudinally extending passageway 24 that terminates at about the point 25. A small port 26 and a larger port 30 27 communicate between the bore 19 and the passageway 24.

Bore 19 is provided with a plug 28, preferably formed of the same material as the housing, that 40 extends from the rear of the housing to a position spaced from the surface 20, and has a rectangular flange 29 through which the plug is secured to the housing by means of screws 30, or the like, a suitable gasket 30' being interposed between the flange and housing. Between the front end of plug 28 and the surface 20, a spacer ring 31 is

arranged and held in place by the plug. Ring 31 carries a smaller ring 32 formed of rubber or other suitable material, and the opening in ring 32 provides a valve seat 33.

A semi-spherical valve 34 which will be referred to as the secondary valve, having a flattened head 35 and an elongated stem 36 is movable into and out of engagement with the valve seat 33. As shown, the rear end of the valve stem 36 is threaded and extends through an opening in the rear wall of a slideable cylinder 37, being held therein by means of nuts 38 threaded on the stem. The cylinder 37 is slideable in the bored front end 39 of plug 28, and inside this cylinder, surrounding valve stem 36, is a coil spring 40. One end of spring 40 bears against the rear wall of cylinder 37, while the opposite end engages the spacer ring 31, the arrangement being such that the spring has a normal bias to hold the cylinder so that the valve 34 is seated, as shown in Fig. 2.

Cylinder 37 has a port 41, a portion of which is always in alignment with a port 42 formed at the front end of plug 28, and the latter port is in fixed alignment with port 21 of the housing. With the arrangement shown, the reduced end 21 of bore 19 constitutes a high pressure chamber 43 which is closed when valve 34 is seated, but when the latter is unseated, gas in chamber 43 will pass through the ports 41, 42 and 21, into the passageway 24. In order to insure proper alignment of ports 41, 42 and 21, and to prevent any possible rotation of the cylinder 37 which might result in misalignment of these ports, a countersunk screw or pin 41' extends through the wall of plug 28 adjacent its bored front end, into an elongated slot 42' formed in cylinder 37. Thus the cylinder cannot rotate but is free to move longitudinally.

Intermediate its ends, plug 28 has a cut-out portion 44 which is in alignment with a similar portion 45 in the housing, and the latter portion is covered by a plate 46, secured to the housing by screws 47, so as to prevent communication between portion 45 and the inner diaphragm chamber 15'. Cut-out portions 44 and 45 form a pilot chamber 48 which communicates with port 26 through a port 49 formed in the plug 28.

The greater portion of the central area of the diaphragm 14 is preferably provided on both sides with discs 50, formed of Bakelite, aluminum or other suitable material, which are secured to the diaphragm by a nut 51 threaded on the reduced end 52 of a reciprocating shaft 53, which end passes through the center of the diaphragm and the discs. Shaft 53 passes through plate 46 and has a seal 54, formed of soft rubber or other suitable material, which is secured to one side of plate 46 as at 55.

The inner end of shaft 53 has a pin 56 extending therethrough, and pivotally secured to each end of this pin is one end of a pair of parallel bell crank levers 57. Levers 57 are pivoted intermediate their ends as at 58 to the adjacent wall of plug 28, and their opposite ends carry small inwardly directed pins 59 which are received in an annular groove 60 formed adjacent the front end of a slideable valve 61, which will be called a primary valve, mounted for movement in a longitudinal guideway 62 formed in the plug.

In the inner diaphragm chamber 15', a flat spring 63 is mounted, having one end secured to the housing as at 64, while its opposite end is secured on the reduced end 52 of shaft 53, as indicated in Fig. 2. Spring 63 has a normal bias

tending to hold the diaphragm in the position shown in Fig. 2. Obviously, movement of the diaphragm inwardly, from its position in Fig. 2 to its position in Fig. 4, will pivot the bell crank levers 57 and slide the valve 61 from its Fig. 2 position to its position in Fig. 4. As will be later explained, inward movement of the diaphragm is accomplished by inhalation of the user of the device, and spring 63 usually assisted by some gas pressure, will return the diaphragm as well as the other moving parts to their initial position as the user exhales.

At its front end, valve 61 carries an insert 65, formed of rubber or other suitable material, which initially seats against a valve seat 66 formed at the reduced end of a passageway 67 that extends longitudinally through the plug 28 and is closed off at the rear by screw 68, or the like. Passageway 67 communicates with a transverse passageway 69 that has its outer end closed by screw 70, or the like.

Extending longitudinally through portion 11 of the housing is a passageway 11, which at its rear end passes through a suitable opening in gasket 30' and continues into communication with the passageway 69. At its front end, passageway 11 joins a transverse passageway 12 which communicates with the high pressure chamber 43. The housing has an annular extension 13 into which is threaded the inner end of an inlet line 14, that leads to a source of supply (not shown) of gas, preferably but not necessarily, oxygen. The intake line 13 communicates with a small passage 15 that leads to the passageway 11.

As more clearly shown in Fig. 6, pilot chamber 48 has a lateral extension 16 that communicates with a passageway 11 formed in the housing, which passageway is reduced to form a valve seat 18 which normally receives a ball valve 19 held in place in a valve chamber 80 by a small coil spring 81. Valve chamber 80 is formed in a threaded extension 82 of the housing and is closed at its outer end by a threaded cap 83 which holds the spring 81 in place against ball 19. Leading diagonally from valve chamber 80 into passageway 24 is a passageway 84.

In order to drill the port 21 and the passageway 12 in the housing it is necessary to provide openings through the adjacent outer wall of the housing, which openings are closed respectively by screws 85 and 86, or the like.

The front of the housing has a nozzle member 87 secured thereto by means of screws 88, or the like, which pass through a flange on the nozzle 87 into the housing, a suitable gasket 90 being inserted between the flange and housing. The opening 91 through the nozzle member communicates at one end with passageway 23, while the other end leads into a rubber tube 92, or the like, which leads to the mouth or nose or both of the user of the device, through any suitable type of mask (not shown).

The operation of the device is as follows:

Fig. 2 shows the initial positions of the parts when the device is ready for use. Gas, up to pressures of say 50 lbs. per square inch, and higher, enters through the inlet 14 and passes in one direction through passageways 11 and 69 into passageway 67 in which it is held by the primary valve 61. In the other direction, gas passes through passageways 11 and 72 into the high pressure chamber 43 where it is held by the secondary valve 34. It will also be observed that with the parts in their initial positions, the pilot chamber 48 is in communication with pas-

sageway 24 through ports 49 and 26 in the plug and housing respectively. Also ball valve 79 is seated to prevent communication through this valve between the pilot chamber and passageway 24.

Normal inhalation through the nozzle 87 will cause the diaphragm 14 to move inwardly from the position shown in Fig. 2 to that shown in Fig. 4, since communication is established between the inner diaphragm chamber 15' and the nozzle through passageways 22 and 23. As the diaphragm moves inwardly, shaft 53 moves to the position shown in Fig. 4, causing the bell crank levers 57 to pivot and slide the valve 61 to the position in Fig. 4, which unseats this valve and permits gas to enter the pilot chamber 48. It will be noted that the front end of the primary valve will close ports 49 and 26 and prevents the gas from passing through these ports into the passageway 24.

Gas continues to enter the pilot chamber 48 until the pressure against the end surface of the cylinder 37 is sufficient to move the cylinder to its position in Fig. 4, which movement unseats the secondary valve 34 and permits gas to pass from the high pressure chamber through ports 41, 42 and 27 into passageway 24, from which it passes through passageway 23 and the nozzle to the user. Gas pressure begins to build up as soon as the gas starts to enter the pilot chamber, and in normal operation the movement of the valve 61 and the cylinder 37 are such that these members are never in contact and remain at least slightly spaced apart.

The amount of gas pressure in pilot chamber 48 need not be great in order to move the cylinder 37. The movement of this cylinder is opposed by spring 40 which need only be sufficiently strong to return the cylinder when no gas pressure is being utilized against the cylinder. Also, the cylinder movement is opposed by the gas in pressure chamber 43, but since the latter pressure acts over a relatively small area, it is quickly overcome. For example, as shown, the outside diameter of the cylinder 37 is about nine times the diameter of the opening at the valve seat 33, and thus the area of the cylinder surface upon which the gas pressure acts in the pilot chamber is about eighty-one times as large as the area acted upon by the gas pressure in chamber 43. Thus, one normal inhalation by the user operates the device and quickly furnishes him with oxygen which he breathes during said inhalation.

Upon completion of the inhalation, the exhaled gases are usually passed to the atmosphere through a valve arrangement in the mask with which we are not concerned here. As inhalation stops, spring 63 and the slight build up of gas pressure in the nozzle and adjacent passageways will return the diaphragm to its initial position, which movement will also return shaft 53, the bell crank levers 57 and valve 61 to their initial positions. It will be observed that as valve 61 returns it uncovers port 49 and allows the gas in the pilot chamber 48 to be released into passageway 24, and the other passages in communication therewith, and this gas will not interfere with the proper seating of the primary valve 61 against its seat 66. Since the escape of gas from chamber 48 will release the pressure against cylinder 37, the spring 40 will return this cylinder to its initial position and seat the secondary valve 34. The device is now ready for the next inhalation by the user. During the sec-

ond inhalation and subsequent inhalations, the small amount of gas remaining in the passageways in direct communication with the nozzle will quickly pass to the user and benefit him until additional gas reaches him in the manner already described.

In an emergency, should the gas pressure in pilot chamber 48 for any reason be insufficient to operate the secondary valve 34, or fail to unseat the valve sufficiently to allow enough gas to pass therethrough to the user, an increase in the inhalation above normal will move the diaphragm further inwardly and increase the forward movement of the primary valve so that the latter will engage cylinder 37 and mechanically move this cylinder to at least substantially complete the opening of valve 34. This mechanical movement of cylinder 37 is indicated in Fig. 5, wherein the cylinder has not quite been moved to its full extent. After this emergency operation of the device, the parts will return to their initial position in the same manner as described in the normal operation.

Valve 79 acts as a pressure relief valve in the event the gas pressure in pilot chamber 48 should build up beyond a desired maximum. For example, for the purpose of illustration, which is not to be considered as limiting to the assumed pressure, we will assume that the cylinder 37 is arranged to operate normally on a pressure of 5 lbs. per sq. in. in the pilot chamber, and that upon completion of inhalations, gas under this assumed pressure will be readily evacuated from the pilot chamber through ports 49 and 26, so that no pressure will remain in the pilot chamber to oppose the return of cylinder 37 to its starting position by the action of spring 40. Now, if the pressure in the pilot chamber could build up beyond 5 lbs., for instance to 10 lbs. per sq. in., the cylinder would still operate to open the valve 34, but its return would be delayed because there would be more gas to evacuate from the pilot chamber before the pressure in the latter would be relieved to permit spring 40 to function. Thus, the timing of the operation of the parts would be interfered with since valve 34 would be locked open at the end of inhalation, and the parts might not fully return to their initial positions by the time the user is ready for his next inhalation. This condition would be avoided, however, if valve 79 were set to open at any time the pressure in the pilot chamber builds up beyond 5 lbs. per sq. in., so that the user would be sure all the parts have returned to their initial position when he is ready for the next inhalation.

In other words, after the desired maximum pressure in the pilot chamber has been determined for normal operation of the cylinder 37, so that opening and closing of the valve 34 is properly timed, the valve 79 is set to open at any time the pressure in the pilot chamber goes above this desired maximum, and any excess pressure in the pilot chamber will be relieved through valve 79, thus insuring a substantially correct maximum pressure in the pilot chamber when it is needed, and substantially complete evacuation of the latter chamber when no pressure is desired therein. As indicated in the previous paragraph, the desired maximum pressure in the pilot chamber might not be 5 lbs. per sq. in. in all instances and this can be determined very easily and corrected for proper operation.

It is believed to be apparent that the invention is well calculated to secure the objects and advantages intended, and while I have shown and

described the preferred form of the invention it will be obvious that modifications may be made therein without departing from the spirit of the invention or from the scope of the subjoined claims.

What is claimed is:

1. In a regulator of the character described having a pilot chamber adapted to receive gas under pressure, a second chamber also adapted to receive gas under pressure, a passageway leading to the user of the regulator, a valve between said passageway and said second chamber, said valve being operable by gas pressure in said first chamber to admit gas from said second chamber into said passageway, and means for supplying gas under pressure to both of said chambers.

2. In a regulator of the character described having a pilot chamber adapted to receive gas under pressure, a second chamber adapted to receive gas under a higher pressure than the gas in said pilot chamber, a passageway leading to the user of the regulator, a valve between said passageway and said second chamber, said valve being operable by gas pressure in said first chamber to admit gas from said second chamber into said passageway, and means for supplying gas under pressure to both of said chambers.

3. In a regulator of the character described having a chamber containing gas under pressure, a passageway leading to the user of the regulator, a valve between said chamber and said passageway, a second chamber adapted to receive gas under pressure, said valve being operable by the pressure of gas in said second chamber to admit gas from said first chamber into said passageway, and means for admitting gas under pressure into said second chamber which means is operable by inhalation of the user of the regulator.

4. In a regulator of the character described having a chamber containing gas under pressure, a passageway leading to the user of the regulator, a valve between said chamber and said passageway, a second chamber adapted to receive gas under a lower pressure than the gas in said first chamber, said valve being operable by the pressure of gas in said second chamber to admit gas from said first chamber into said passageway, and means for admitting gas under pressure into said second chamber which means is operable by inhalation of the user of the regulator.

5. In a regulator of the character described having a chamber containing gas under pressure, passageways leading from said chamber to the user of the regulator, a valve initially seated between said chamber and passageways, a second and larger chamber adapted to receive gas under pressure from the same source as said first chamber, said valve being adapted to be unseated by gas pressure in the second chamber, and means operable by inhalation of the user of the regulator for admitting gas under pressure into said second chamber.

6. In a regulator of the character described, a large chamber and a small chamber adapted to receive gas under pressure, a common gas supply line between said chambers, a valve initially seated to oppose admission of said gas into said large chamber, a passageway between said small chamber and the user of the regulator, a second valve initially seated to prevent the flow of said gas out of said small chamber into said passageway, said second valve being adapted to be unseated by gas pressure in said large chamber, and means for unseating said first valve by in-

halation of the user of the regulator to admit gas under pressure into said large chamber.

7. In a regulator of the character described, a large chamber and a small chamber adapted to receive gas under pressure, a common gas supply line between said chambers, a valve seated to oppose admission of said gas into said large chamber, a passageway between said small chamber and the user of the regulator, a second valve initially seated to prevent the flow of gas out of said small chamber into said passageway, said second valve being adapted to be unseated by gas pressure in said large chamber, an initially opened port between said large chamber and said passageway, and means for unseating said first valve by inhalation of the user of the regulator to admit gas under pressure into said large chamber and simultaneously to close said port.

8. A regulator of the character described in claim 6 wherein said means comprises a diaphragm, a reciprocating shaft connected to said diaphragm, and a bell crank lever connected between said shaft and said first valve.

9. A regulator of the character described in claim 7 wherein said means comprises a diaphragm, a reciprocating shaft connected to said diaphragm, and a bell crank lever connected between said shaft and said first valve.

10. In a regulator of the character described, a chamber containing gas under pressure, a passageway between the chamber and the user of the regulator, a valve initially seated to prevent the flow of gas out of said chamber into said passageway, a second chamber also adapted to receive gas under pressure, a second valve in the latter chamber initially seated to oppose admission of gas into said second chamber, said first valve being adapted to be completely opened by gas pressure in said second chamber under normal conditions, and means for unseating said second valve by normal inhalation of the user to admit gas under pressure into said second chamber, said means being further operable by inhalation of the user above normal to mechanically assist the gas pressure in said second chamber in opening said first valve.

11. A regulator of the character described in claim 10 wherein said means comprises a diaphragm, a reciprocating shaft connected to said diaphragm, and a bell crank lever connected at one end to said shaft and at its other end to said second valve.

12. A regulator of the character described in claim 6 wherein said first valve comprises a member operable to mechanically unseat said second valve in the event the gas pressure in the large chamber is insufficient to unseat same.

13. A regulator of the character described in claim 7 wherein said first valve comprises a member operable to mechanically unseat said second valve in the event the gas pressure in the large chamber is insufficient to unseat same.

14. In a regulator of the character described, a large chamber and a small chamber adapted to receive gas under pressure, a common gas supply line between said chambers, a valve initially seated to oppose admission of said gas into said large chamber, a passageway between said small chamber and the user of the regulator, a second valve initially seated to prevent the flow of said gas out of said small chamber into said passageway, said second valve being adapted to be unseated by gas pressure in said large chamber, means for unseating said first valve by inhalation of the user of the regulator to admit gas

under pressure into said large chamber, and means for returning said first valve to its initial position after inhalation is completed.

15. In a regulator of the character described, a large chamber and a small chamber adapted to receive gas under pressure, a common gas supply line between said chambers, a valve initially seated to oppose admission of said gas into said large chamber, a passageway between said small chamber and the user of the regulator, a second valve initially seated to prevent the flow of said gas out of said small chamber into said passageway, said second valve being adapted to be unseated by gas pressure in said large chamber, and a separate means for returning each of said valves to their initial positions after inhalation is completed.

16. In a regulator of the character described having a diaphragm movable in one direction by inhalation of the user, a spring for moving the diaphragm in the opposite direction, a chamber containing gas under pressure, a passageway leading from said chamber to the user, a valve initially seated to oppose the flow of gas from said chamber into said passageway, a second chamber adapted to receive gas under pressure to unseat said valve, a second valve in said second chamber initially seated to oppose admission of gas into the latter chamber, and means for unseating said second valve by movement of said

diaphragm from inhalation of the user to admit gas under pressure into said second chamber to unseat said first valve.

17. A regulator of the character described in claim 16 wherein said means comprises a reciprocating shaft connected to said diaphragm and a bell crank lever connected between said shaft and said second valve.

18. A regulator of the character described in claim 16 wherein said second valve comprises a member operable to mechanically unseat said first valve in the event the gas pressure in said second chamber is insufficient to unseat same.

19. A regulator of the character described in claim 6 wherein a relief valve is associated with said large chamber to relieve excess pressure therein beyond a predetermined maximum.

20. A regulator of the character described in claim 7 wherein a relief valve is associated with said large chamber to relieve excess pressure therein beyond a predetermined maximum.
